UNITED STATES PATENT OFFICE

2,438,650

CONSTRUCTION OF RETRACTABLE
LANDING GEAR

Raymond Saulnier, Paris, France

Application February 13, 1942, Serial No. 430,821
In France May 15, 1940Section 1, Public Law 690, August 8, 1946
Patent expires May 15, 1960

15 Claims. (Cl. 244—102)

1

The present invention relates to retractable landing gear of the type including a shock absorber which carries the wheel, pivoted to a fixed point of the airplane structure and maintained in the landing or extended position by a breakable strut pivoted on the one hand to a fixed point of the airplane and, on the other hand, to a point of the shock absorber.

The invention relates more particularly to landing gear of this type, in which the point at which the strut is pivoted to the shock absorber is located close to the lower end of the cylinder of the shock absorber, which ensures a very good resistance during landing.

More specifically, the invention relates to retractable landing gear in which the strut is made of two portions pivoted to each other substantially at the middle point of the strut, in such a manner that, when the gear is in the landing position, the point of articulation of the two portions of the strut is beyond the dead center position, so as to improve safety when landing, independently of the locking of the strut.

According to the invention, the folding or retracting of the landing gear is effected in two steps, the first of which consists, after the strut has been released, in breaking it so as to cause, in the particular case just above mentioned, the point of articulation to pass to the other side of the dead center line, the second step being performed by the action of a jack pivoted on the one hand to a fixed point of the airplane and, on the other hand, to the end of a lever rigid with the shock absorber, so as to cause the latter to pivot about the point at which it is mounted on the airplane.

One of the most serious difficulties which have to be dealt with in retractable landing gear, is to ensure a retraction of a gear with the minimum of force, which implies an efficient utilization of the power of the retracting means.

An object of the present invention is to provide a retracting device such that the first step, which starts the breaking of the strut, and the second step which causes the shock absorber to pivot about its point of articulation on the airplane, are produced by a thrust directed along a line making an angle as small as possible with the optimum direction, account being taken of the power to be exerted.

For this purpose, according to a feature of my invention, the strut includes a system of levers intended to break this strut and, in particular, to move the point of articulation thereof from one side to the other of the dead center line.

According to another feature of the invention, the lifting device proper is arranged in such

2

manner that the lever arm on which the jack is to act lengthens, during the lifting movement, as the resistance itself increases, whereby the power required to be exerted by the jack never reaches very high values, since the force required to be exerted at the end of the movement is relatively small.

Other features of my invention will appear from the following detailed description of some specific embodiments thereof.

Preferred embodiments of my invention are hereinafter described, with reference to the accompanying drawings, merely by way of example. In the drawings:

15 Fig. 1 is a diagrammatic front view of a landing gear made according to the invention;

Fig. 2 is a detailed diagrammatic view showing on an enlarged scale the means for releasing the strut and breaking it;

20 Fig. 3 is a view similar to Fig. 1, showing another embodiment of the invention;

Fig. 4 is a detailed longitudinal sectional view showing on an enlarged scale the valve of the operating jack used in connection with the device of Fig. 3.

In the embodiments of Figs. 1 and 2, G is the shock absorber which carries a wheel W and is pivoted at H to a fixed part M of the airplane. The shock absorber may be maintained or not 30 in its plane, parallel to the fore-and-aft plane of symmetry of the airplane, by a thrust bar, the latter being pivoted to a fixed part of the airplane at a point located behind point H, so that the whole can pivot about a longitudinal 35 axis passing through these two points. The landing gear further includes a strut constituted by two portions A and A' pivoted to each other near the middle point of the strut at B. These two portions are locked in the landing position by 40 a locking member C which is shown in a more detailed manner by Fig. 2. This locking member is preferably controlled pneumatically by a valve D. E and F are the points where the strut is pivoted to the airplane and to the shock absorber, respectively.

The retraction of the landing gear is obtained by swinging the shock absorber G about point H, this movement being produced by the action of a jack V, one of whose ends is pivoted to the 45 airplane at a point J, while the other end is pivoted to a lever arm I rigid with the shock absorber.

Reference character T designates the operating member, N is the compressed air inlet, K a distributor for controlling the inflow of oil under pressure and Q a conduit through which oil is fed to the distributor. Distributor K is further

connected through pipes K^1 and K^2 to the opposite ends of jack V. Finally, valve D is connected through a pipe d to a pneumatic piston P housed in strut A, A'.

This device operates in the following manner:

The first movement of the operating lever T, in the direction of arrow f^1 , opens valve D, which causes compressed air to be fed into pipe d. Pneumatic piston P is actuated by this compressed air and pushes lever L, pivoted about an axis O, so as to move the locking member C of the lever L (see Fig. 2), into inoperative position.

During the second part of this first movement, a projection R on lever L strikes a corresponding projection R' of portion A' of the strut, whereby the thrust of piston P breaks the strut just when the two projections disengage from each other. At this time, the movement of piston P is stopped by a lug U. During this movement, the point B about which the two portions of the strut are pivoted to each other, passes from a position below line E—F (where it was jammed in order to increase safety in case of non-operation of the locking means) to the position B' on the other side of said line E—F. The operating lever T is now at the end of its first movement in the direction of arrow f^1 .

The second movement of this operating lever T, in the direction of the arrow f^2 , permits oil under pressure to pass through distributor K and through conduit K^1 into the near end of the jack V. This pushes lever I and causes the shock absorber to swing on its pivot H, whereby the landing gear is fully folded.

In the embodiment which has just been described, the operating lever T is given two successive movements, one serving to control the pneumatic piston which starts the breaking of the strut, and the other operating the jack, which finishes the retroacting operation.

In the embodiment shown in Fig. 3, the pneumatic control valve D is located between jack V and the point J of fixation thereof to the airplane. In this embodiment, the operation of the lifting device is simplified because only the flow of oil through the distributor K requires to be controlled by the control element X.

When the control lever X of Fig. 3 is moved, oil under pressure is fed through conduit K^1 to the jack, which tends to push lever I, on the one hand, and to open valve D on the other hand. As lever I resists the thrust thus transmitted thereto, because strut A—A' is locked and therefore cannot break, jack V compresses spring Y (see Fig. 4) and permits valve D to be opened by the compressed air from the pipe N, so that compressed air is passed to operate the piston P, so as to move locking member C into inoperative position and start the breaking of the strut in the manner explained above. The jack then bears against the piece Z, provided in the valve D for limiting its movement, and pushes on the lever I so as to retract the shock absorber.

The landing gear according to the invention has many advantages, among which the following may be cited:

First, the safety obtained when landing is very high, since the shock absorber is well adapted to resist transverse stresses, because it is braced at a very low point by the strut. The strut cannot break accidentally since, even when it is not positively locked, said strut is biased in the extended position by the compression stresses, resulting from displacement of the articulation B of the strut with respect to the direction E—F of the

landing stresses. Therefore there is practically no risk of an accidental folding of the gear during landing, even under the most difficult conditions.

5 Further, reliable extension of the landing gear is assured by the gravity effect of the weight of the landing gear, the counter-pressure in the jack V, and the action of the elastic cable S, which is stretched between the strut A, A' and the frame M.

10 Another advantage of the landing gear, according to the invention, derives from the fact that the power necessary for retracting the gear is reduced to a minimum. As above explained, the first movement, which starts the breaking of the strut, by unlocking it, necessitates only a very small force in view of the particular arrangement of the levers and the projections carried by the parts of the strut. Furthermore, the 15 effective leverage of the arm I, on which the lifting jack acts, increases as the force required increases, as above explained.

20 While I have, in the above description, disclosed what I deem to be practical and efficient 25 embodiments of the present invention, it should be well understood that I do not wish to be limited thereto, as changes may be made in the arrangement, disposition and form of the parts, without departing from the principle of the present 30 invention, as comprehended within the scope of the appended claims.

What I claim is:

1. A retractable landing gear including a shock 35 absorber pivoted to the airplane proper, a member adapted to run on the ground carried by said shock absorber, a jointed strut pivoted at one end to the airplane proper and at the other end to the shock absorber, said strut being broken in the folded position of the landing gear and straightened in the extended position of said landing gear, means for locking said strut in the landing position, means carried by the strut for bringing said locking means out of action and substantially simultaneously starting the breaking 40 of said strut, and a jack interposed between the airplane proper and said shock absorber for finishing the folding movement started by the above mentioned means.

2. A retractable landing gear including a shock 50 absorber pivoted to the airplane proper, a member adapted to run on the ground carried by said shock absorber, a jointed strut pivoted at one end to the airplane proper and at the other end to the shock absorber, said strut being made of two 55 parts pivoted to each other at the middle point of the strut and being broken in the folded position of the landing gear and straightened in the extended position of said landing gear so that said middle point passes slightly beyond the dead center line of the strut, means for locking said strut in the landing position, means carried by the strut for bringing said locking means out of action and substantially simultaneously bringing back said middle point on the other side of said dead center line, and a jack interposed between the airplane proper and said shock absorber for finishing the folding movement started by the above mentioned means.

3. A retractable landing gear including a shock 70 absorber pivoted to the airplane proper, a member adapted to run on the ground carried by said shock absorber, a jointed strut pivoted at one end to the airplane proper and at the other end to the shock absorber, said strut being broken 75 in the folded position of the landing gear and

straightened in the extended position of said landing gear, spring means for locking said strut in the landing position, pneumatic means carried by the strut for bringing said locking means out of action and substantially simultaneously starting the breaking of said strut, a jack interposed between the airplane proper and said shock absorber for finishing the folding movement started by the above mentioned means, and means for feeding liquid under pressure to said jack.

4. A retractable landing gear including a shock absorber pivoted to the airplane proper, a member adapted to run on the ground carried by said shock absorber, a jointed strut pivoted at one end to the airplane, said strut being broken in the folded position of the landing gear and straightened in the extended position of said landing gear, spring means for locking said strut in the landing position, pneumatic means carried by the strut for bringing said locking means out of action and substantially simultaneously starting the breaking of said strut, a jack interposed between the airplane proper and said shock absorber for finishing the folding movement started by the above mentioned means, hydraulic means for feeding liquid under pressure to said jack, and a common operating member for successively operating said pneumatic means and said hydraulic means.

5. A retractable landing gear including a shock absorber pivoted to the airplane proper, a member adapted to run on the ground carried by said shock absorber, a jointed strut pivoted at one end to the airplane proper and at the other end to the shock absorber, said strut being broken in the folded position of the landing gear and straightened in the extended position of said landing gear, spring means for locking said strut in the landing position, pneumatic means carried by the strut for bringing said locking means out of action and substantially simultaneously starting the breaking of said strut, a jack interposed between the airplane proper and said shock absorber for finishing the folding movement started by the above mentioned means, hydraulic means for feeding liquid under pressure to said jack, a lever adapted to be given two different movements, means operated by said lever for one of said movements for operating said pneumatic means and means operated by the other movement of said lever for operating said hydraulic means.

6. A retractable landing gear including a shock absorber pivoted to the airplane proper, a member adapted to run on the ground carried by said shock absorber, a jointed strut pivoted at one end to the airplane proper and at the other end to the shock absorber, said strut being broken in the folded position of the landing gear and straightened in the extended position of said landing gear, spring means for locking said strut in the landing position, pneumatic means carried by the strut for bringing said locking means out of action and substantially simultaneously starting the breaking of said strut, a jack interposed between the airplane proper and said shock absorber for finishing, when expanded, the folding movement started by the above mentioned means, said jack having lost motion to give it a slight play at the beginning of its operation to complete the folding movement, hydraulic means for feeding liquid under pressure to said jack, an air valve for controlling said pneumatic means adapted to be opened by the expanding movement of said jack corresponding to the tak-

ing up of said play, and valve means for operating said hydraulic means.

7. A retractable landing gear according to claim 6 further including a lever adapted to operate said last mentioned valve means in such manner that a first displacement of said lever causes the jack to take up its play and movement in the same direction causes said jack to finish the folding of the landing gear.

10. 8. In a retractable landing gear for airplanes, the combination of, an elongated member pivoted at one end to the airplane proper and adapted to swing from a downwardly extending position to a substantially horizontal position an airplane supporting member carried upon the free end of said elongated member, a jack pivoted at one end to the airplane and at its other end to the upper part of said elongated member for operating said elongated member into inoperative horizontal position a jointed strut pivoted at one end to the airplane proper and at the other to the elongated member and being movable from a folded position in which said elongated member extends substantially horizontally to an extended position in which said elongated member extends downwardly, said strut comprising a pair of strut members having a pivotal connection which moves past the dead center of the strut when the strut approaches its extreme extended position, latch means on the strut bridging said pivotal connection so as to hold said strut in its extended position, and fluid operated means on the strut for operating said latch means into inoperative position and for moving said pivotal connection toward folded position across the dead center of the strut, so as to break the strut.

9. In a retractable landing gear for an airplane involving an elongated member having a ground engaging element at its lower end and means at its upper end for pivotal connection with the airplane to enable said elongated member to be retracted from a substantially vertical ground engaging position to a substantially horizontal retracted position, and a foldable strut for bracing said elongated member in its ground engaging position, said foldable strut comprising an upper section pivoted to the airplane and a lower section pivoted to a lower end portion of said elongated member, an off-center break joint swingably connecting the upper and lower sections together at a point offset from the longitudinal axes of said sections, said break joint including a fixed joint element on the lower section projecting alongside of an adjacent portion of the upper section and having a cam surface, said break joint further comprising a latch pivoted on the upper section having a cam operatively engageable with the cam surface whereby the lower section is swung away from the upper section whenever said latch is moved on its pivot in one direction, said latch further having a detent portion latching with a portion on the lower section when the sections are in their extended positions, a hydraulic cylinder and piston assembly mounted and operating longitudinally on said upper section with a portion of its piston engageable with said cam to move it in said one direction so as to sequentially disengage said detent portion from latching relation to the lower section and swing said lower section relative to said upper section thereby partially folding the strut, and hydraulic means for completing the folding of the strut.

10. In a retractable landing gear for an airplane of the type involving a normally vertical

elongated member having a ground engaging element at its lower end and means for pivoting it at its upper end to an airplane, and a foldable strut extending between the lower part of said elongated member and a part of the airplane, said strut comprising an upper section pivoted at its upper end to the airplane and a lower section pivoted at its lower end to the lower part of said elongated member and an off center break joint swingably connecting the sections, latch means for locking the sections in extension of each other, said latch means comprising a cam pivoted on one section and a cam surface on the other section, a fluid cylinder and piston assembly mounted longitudinally on said one section, said piston being operatively engageable with said cam so as to move said cam against said cam surface so as to swing the sections relative to each other sufficiently to break the joint and permit the strut to move into folded position when said assembly is operated, and means for completing the folding of the sections.

11. In a retractable landing gear for an airplane, a normally vertical shock-strut pivoted at its upper end to the airplane, a foldable brace strut extending between the lower part of the shock-strut and a part of the airplane remote from the pivotal point of the shock-strut, said foldable brace strut comprising upper and lower sections pivoted to the airplane and the lower part of the shock strut, respectively, and an off center break joint pivoting the sections together for folding relative to each other and for substantial longitudinal alignment of the sections in their unfolded position, said break joint comprising a movable latch member mounted on one of the sections and lockably engageable with the other section in the aligned relation of the sections, said latch member having a cam portion engageable after release of the latch member from said other section with a portion of said other section so as to move the latter so as to break the joint and impart preliminary movement of the sections relative to each other toward folded position, said upper section having a hollow portion, and operating means comprising a fluid piston and cylinder assembly mounted within said hollow portion and longitudinally with respect to the upper section and operatively engageable with said movable latch member.

12. In a retractable landing gear for an airplane, the combination of a longitudinally acting shock absorber pivoted at one end to the airplane for swinging from a depending vertical operative position to a substantially horizontal inoperative position, a ground engaging element on the free end of said shock absorber, means for moving said shock absorber into and out of operative position, a foldable strut pivoted at one end to the airplane and at its other end to the shock absorber adjacent to its said free end to brace the shock absorber in its operative position, said foldable strut comprising a pair of sections, hinge means arranged off center on the side of the strut remote from the shock absorber and hingedly connecting the sections together and permitting the sections to pivot out of longitudinal alignment to enable the strut to fold toward the shock absorber as the shock absorber is swung upwardly from its vertical operative position toward its inoperative horizontal position, the off center location of the pivotal point of said hinge means precluding the pivoting of said sections out of longitudinal alignment in the opposite direction, latch means bridging and interconnecting the

5 hinged ends of the strut sections for locking the sections when in longitudinal alignment, and cooperating means carried by the adjacent ends of said strut sections for releasing said latch means and for moving the sections past their off-center relation toward folded position to permit the sections to pivot in a strut-folding operation.

13. In a retractable airplane landing gear, a longitudinally acting shock absorber pivoted at its upper end to the airplane to extend downwardly in extended position and having a ground engaging element at its lower end, a foldable strut pivoted at its lower end to the lower part of said shock absorber and at its upper end to the airplane at a point at one side of the pivotal point of the shock absorber, said strut comprising a pair of sections, means hinging the sections together at their inner ends to fold toward the shock absorber as the landing gear is retracted to inoperative position and to reach a position past dead center when restored to aligned position as the landing gear is extended to operative position, locking means for locking the sections together as they move into their aligned position, a lever connected to the upper end of the shock absorber and turning on the pivot of the shock absorber, a jack located at the strut side of the shock absorber and having one end connected to said lever and its opposite end to the airplane, and operating means for working the jack to retract and extend the shock absorber, said operating means including means responsive to the operation of said operating means for releasing said locking means in advance of retraction of said shock absorber by said operating means.

14. A retractable landing gear as described in claim 8 wherein said last-named means includes a pivoted cam element on one of the strut members which engages a cooperating portion on the other of the strut members, and wherein said latch means includes a latch element carried by said cam element and engageable with a second portion on said other of the strut members to latch the strut members, whereby the movement 40 of the latch means towards inoperative position causes the cam element to move the strut members relative to each other and thereby break the strut.

15. A retractable landing gear as described in 50 claim 8 wherein said jack comprises a fluid operated cylinder-piston unit and a valve mounted on one end of the cylinder, said valve being responsive to the fluid pressure in said unit and controlling the supply of fluid to said fluid operated means on the strut.
